UNITED STATES PATENT OFFICE.

BENJAMIN McINNERNEY, OF COUNCIL BLUFFS, IOWA.

ELECTROMAGNETIC SWITCH.

1,364,944.

Specification of Letters Patent. Patented Jan. 11, 1921.

Application filed December 20, 1916. Serial No. 138,020.

To all whom it may concern:

Be it known that I, BENJAMIN McINNERNEY, a citizen of the United States, and a resident of Council Bluffs, in the county 5 of Pottawattamie and State of Iowa, have invented a new and useful Improvement in Electromagnetic Switches, of which the following is a specification.

My invention relates to electromagnetically operable switches and it has particular relation to switches of the so-called lock-out type that operate only under predetermined circuit conditions.

My invention has, for one of its objects, 15 to provide a switch of the above-indicated character that is simple in construction and efficient in operation to close a circuit controlled by it only when the current traversing a magnetizing coil of the switch falls to 20 a predetermined value.

Switches of the same general character as that of my invention have been provided heretofore, but they usually comprised single series actuating coils. Such switches 25 are not well adapted for certain applications because of the relatively short period during which the current exceeds the predetermined value and because of the rapidity of the changes in current value 30 caused by the operation of switches or the acceleration of the motor, as the case may be. When a motor is supplied with energy from a source of variable electromotive force, the switches may open in case the 35 electromotive force falls to a relatively low value, and the insertion of the armature resistor tends to decrease the electromotive force applied to the motor rather than to increase it, under such conditions.

40 In switches constructed in accordance with my invention, the actuating coils for effecting the closing of the switches are connected across the line or in shunt relation to the translating devices, the circuits of 45 which are to be controlled. Each of the switches is provided with a series coil which operates to prevent the closing of the switch except when the coil is energized below a predetermined value. By means of the arrangement described above, a force tending 50 to close the switch is always available except upon failure of voltage.

In the preferred form of my invention, 55 armature members are actuated respectively by electromagnets energized by the series coil and by the shunt coil. The armature

controlled by the shunt coil is operatively connected to the movable member of a switch by means of a spring. When the shunt coil is energized, the armature is attracted and the switch is closed if the series coil is energized below a predetermined value. If, however, the current traversing the series coil exceeds the predetermined value, the movable switch member is held in 60 its open position, the spring for operatively connecting the armature controlled by the shunt coil to the movable switch member is placed under stress and the switch is closed immediately upon the current falling to the 65 predetermined value.

My invention is adapted for use in connection with the acceleration of electric motors. An electric motor may be started by an arrangement comprising a series of 75 switches constructed in accordance with my invention for successively operating to shunt resistors in the armature circuit of the motor and for inserting a resistor in circuit with the shunt field-magnet winding 80 of a motor. Each of the switches, except the last to close, operates to shunt a portion of the series coil of the succeeding switch to close in order to insure that the switches 85 operate in the proper sequence.

The details of my invention will be described in connection with the accompanying drawings, in which Figure 1 is a side view, partially in elevation and partially in section, of a switch constructed in accordance with my invention. Fig. 2 is a front view, in elevation, of the switch of Fig. 1. Fig. 3 is a side view, in elevation, of a modification of the switch shown in Fig. 1. Fig. 4 is a diagrammatic representation of a 95 system embodying a plurality of switches similar to that shown in Fig. 3 for controlling the circuits of an alternating-current motor. Fig. 5 is a diagrammatic representation of a direct-current system embodying a plurality of switches constructed in accordance with my invention. Fig. 6 is a plan view of a switch of modified form the 100 circuits and apparatus of a system in connection with which it is employed being 105 diagrammatically shown. Fig. 7 is a side view, in elevation, of the switch shown in Fig. 6.

Referring particularly to Figs. 1 and 2, a base plate 1 of slate, or other suitable material, supports a pair of stationary contact members 2. A pair of coacting movable

switch members 3 are rigidly connected to a member 4 that is pivotally supported at 5 by a bracket 6.

5 A stationary magnetizable member 7, of substantially U-shape, is provided with an energizing coil 8 that is connected in shunt relation to the translating device controlled by the switch. In the present case, the switch is adapted to be employed in connection with alternating-current circuits, and 10 the coil 8 is accordingly connected between two of the line conductors.

An armature 9, which is also pivotally supported at 5, is operatively connected to 15 the member 4 by means of a spring 10, a pivotally mounted member 11 and a spring 12. Three series coils 14, which are supported by the magnetizable member 7, are provided with adjustable core members 15 20 which coact with an armature member 16. As shown in Fig. 2, each of the coils 14 is provided with an intermediate terminal in order that the number of turns may be controlled, for reasons to be later described. 25 The armature member 16 is secured to the pivotally mounted member 11.

While I have shown and described three series coils for preventing the closing of the switch, under predetermined conditions, it is 30 obvious that two of the coils may be omitted, since the current traversing one phase of a three-phase circuit corresponds substantially to that traversing the other circuits. It is immaterial, also, whether a single shunt coil 35 or a plurality of such coils is employed for effecting and maintaining the closure of the switch.

It may be assumed that the switch mechanism shown in Figs. 1 and 2 occupies its 40 open position. When a line switch, or other suitable switch, is closed, the shunt coil 8 is energized and the armature member 9 is attracted to its illustrated position (Fig. 1). If, for example, the switch is employed in 45 connection with an electric motor, a rush of current occurs in the motor circuit which includes, in the case of a three-phase motor, each of the series coils 14.

If the coils 14 are energized above a 50 determined value, the armature member 16 and the connected mechanism, including the member 4 and the movable switch arms 3, are retained in their respective positions illustrated in Fig. 1. The spring 10 has been 55 placed under tension by the relative movement of the armature 9 and the member 11.

When the currents traversing the circuits comprising the series coils 14 fall to such 60 values that the force of the spring 10 is sufficient to overcome the pulls exerted by the core members 15, the member 11, the member 4 and switch arms 3 are actuated to the closed position of the switch. The coil 8 is energized by a substantially constant force 65 during such time as the line switch is closed.

Reference may now be had to Fig. 3, in which is illustrated a modification of the switch shown in Figs. 1 and 2. Similar reference numerals are employed to designate corresponding parts. The operation of the 70 switch shown in Fig. 3 is substantially identical with that of the switches previously described, but certain of the structural details have been modified. A movable switch arm 17 carries two contact members 18 75 which coact with corresponding stationary contact members 19. The contact members 18 are connected by a flexible shunt conductor to a terminal 20 which may be connected to one phase of a three-phase circuit to 80 which the members 19 are respectively connected.

The movable arm 17, which is pivotally mounted at 21, is provided with a projecting member 22. An armature member 23, 85 which is also pivotally supported at 21, is operatively connected to the arm 17 by means of a spring 24, the respective ends of which engage projecting portions of the movable arm 17 and the armature member 90 23. The projection 22 carries, at its lower end, an adjustable member 25 which constitutes the armature member of an electromagnet comprising a series magnetizing coil 26. The coil 26, which is diagrammatically 95 represented, is provided with an intermediate terminal in order that the numbers of turns may be controlled, as will be later described in connection with the various systems embodying switches constructed in accordance 100 with my invention.

The operation of the switch differs in no material respect from that of the switch previously described. The energization of the shunt coil 8 causes the armature member 105 23 to exert a force upon the spring 24 tending to close the switch. If the current traversing the series coil 26 is of such value that the force exerted upon the member 25 retains the member 17 in its open position, the 110 spring 24 remains under compression. When the current traversing the coil 26 falls to the predetermined value at which the mechanism is adjusted to operate, the spring 24 effects the actuation of the member 17 to its 115 closed position.

A system for controlling the secondary circuit of a three-phase induction motor and embodying a plurality of switches similar to that shown in Fig. 3, is illustrated in Fig. 4. 120 Similar reference numerals are employed to designate parts corresponding to those of the switch shown in Fig. 3. The several switches 27, 28 and 29 are mounted in alignment, a single shaft 30 constituting a pivotal support for the respective switch members 17. The shaft 30 is secured to three arms 31, each of which corresponds to the projecting portion of the armature member 23 of the switch of Fig. 3. The shaft 30 is provided 125 130

with an arm 32 which constitutes the armature member of an electromagnet or solenoid 33. The solenoid 33 is supplied with energy from the line conductors for supplying energy to the primary windings of an electric motor 34.

Each of the switches 27, 28 and 29 controls a section of each of resistors 35 that are connected in circuit with the secondary 10 windings of the induction motor 34. The switches are respectively provided with series coils 36, 37 and 38 that are connected in series relation with one of the phase windings of the secondary winding. The coils 37 15 and 38 are provided with an intermediate terminal that is connected to the preceding switch to close.

It may be assumed that it is desired to start the motor 34. A line switch 38^a may 20 be closed to connect the motor to any suitable source of alternating current. The solenoid 33 is energized to attract the armature member 32 and thereby place the several springs 24 under compression. The forces 25 exerted by the respective springs 24 tend to close the corresponding switches. A heavy rush of current traverses the secondary circuit, however, upon the closing of the line switch 38^a and the coils 36, 37 and 38 are 30 energized to retain the movable switch members 17 in their open positions.

When the current traversing the secondary circuit falls to a predetermined value, the force exerted by the series coil 36 decreases to such degree that it is less than 35 that exerted by the spring 24 tending to close the switch. The switch 27 then closes to shunt one section of each of the resistors 35, and, at the same time, to shunt a portion of 40 the turns of the series coil 37.

The switches 28 and 29 do not close simultaneously with the switch 27 for the reason that the coils 37 and 38 are provided with a number of turns in excess of the required 45 number to hold the switch open when the current is above the predetermined value. When a shunt circuit is established for a portion of the turns of these coils, the remaining turns are equal to the turns of coil 50 36. This arrangement insures that the switches operate in the proper sequence.

A second rush of current traverses the secondary circuit upon the closing of the switch 27, and the switch 28 remains in its 55 open position until the current has again fallen to the predetermined value. In like manner, the switch 28 shunts a section of each of the resistors 35 and shunts a portion of the turns of the series coil 38 in order 60 that the switch 29 may operate when the current again falls to the predetermined value.

By means of the arrangement described above, a single actuating coil may be employed for closing a plurality of switches.

This coil is energized upon the closing of the main switch. The operation of the switches in a definite order is insured by providing the lockout coils with an abnormal number of turns that are energized previous to the closing of the preceding switch in the series.

Reference may now be had to the system illustrated in Fig. 5, in which a series of switches constructed in accordance with my 70 invention is employed for controlling the resistance of the armature circuit and of the circuit of the shunt field-magnet winding of a direct-current motor. Line conductors 39 supply current to an electric motor having 80 an armature indicated at 40 and a shunt field-magnet winding 41. Resistors 42, 43 and 44 are respectively controlled by electromagnetic switches 45, 46 and 47.

Each of the switches 45, 46 and 47 is provided with an actuating coil 48, the respective terminals of which are connected to the line conductors 39. The several switches are provided, also, with coils 49 that are connected in series with the armature winding 40. 85 A portion of each of the series coils of switches 46 and 47 is adapted to be shunted upon the closing of the preceding switch. The additional turns of the series coils are provided in order to insure that the switches 90 close in proper sequence. The shunt coils 48, when energized, tend to effect the closing of the corresponding switches. The series coils 49 oppose the force of the shunt coils 48 in accordance with the current traversing the armature circuit of the motor.

A shunt circuit for a resistor 50, that is in circuit with the shunt field-magnet winding 41, is controlled by an electromagnetic switch 51. This switch is provided with a 105 series closing coil 52 and a shunt coil 53 which opposes the force of the coil 52.

When a line switch 54 is closed, a rush of current traverses the armature circuit of the motor which extends from positive line 110 conductor 39, through the several series coils 49, the resistors 42, 43 and 44, series coil 52, and armature 40, to negative line conductor 39. The several shunt actuating coils 48 are energized upon the closing of line 115 switch 54.

The shunt coil 48 of switch 45 tends to close the switch, but this action is prevented by the force of series coil 49 as long as the current traversing the motor circuit 120 exceeds a predetermined value. When the current falls below the predetermined value, the force exerted by the series coil is less than that of the shunt coil 48, and the switch is closed to complete a shunt circuit for the 125 resistor 42 which comprises a portion of the series coil 49 of switch 46.

A second rush of current through the motor circuit occurs upon the closing of switch 45, and switch 46 remains in its open position 130

until the current falls below the predetermined value, as in the case of switch 45. The closing of switch 47 is effected, in a similar manner, to complete a shunt circuit 5 for the resistor 44 and thus complete the acceleration of the motor by shunting the starting resistors.

During the above-described acceleration of the motor, the switch 51 remains in a 10 closed position by reason of the fact that the effective turns of the series coil 52 are such that the force exerted by the coil 52 is materially greater than that of the shunt coil 53. The closing of switch 47 completes a shunt 15 circuit for a portion of the coil 52. When the current traversing the coil 52 falls to a predetermined value, the shunt coil 53 effects the opening of the switch to insert the resistor 50 in circuit with the field-magnet 20 winding 41. The motor is further accelerated by the resultant weakening of its field.

Referring now to Figs. 6 and 7, a switch 55 consists of four pivotally mounted switch members 56, 57, 58 and 59, of magnetizable material, which respectively coact with corresponding stationary contact members 60. A single coil 61, which is adapted to be connected in shunt relation to an electric motor, energizes a magnetic circuit which comprises 30 all of the movable members 56, 57, 58 and 59. It will be understood that separate contact members may be mounted upon the outer ends of the several movable arms if such arrangement is necessary or desirable.

35 The operation of each of the switch members 56, 57, 58 and 59 is controlled by a series coil 62. Each of the coils 62, except that for controlling switch member 56, is provided with an intermediate terminal in order 40 that the number of turns of the several coils may be varied in a manner previously described in connection with the switches shown in Figs. 1 to 5, inclusive. The movable contact members 56, 57, 58 and 59 are 45 electrically connected to each other by means of members 63 and 64. The stationary contact members 60 are insulated from each other.

Referring particularly to Fig. 6, line conductors 65 and 66 supply current to a direct-current electric motor, the armature of which is indicated at 67. Each of the switch members controls a resistor 68 that is in series with the armature winding of the motor. It 50 may be assumed that the motor is at rest and that the several switch members are in their respective open positions, as illustrated in Figs. 6 and 7.

To start the motor, a line switch 69 is 60 closed to complete the motor circuits and to establish a circuit for energizing the shunt coil 61. The coil 61 energizes a magnetic circuit comprising a pole piece 70 and the several switch members which are adjacent 65 to the pole piece. The force exerted by the

magnetic circuit mentioned above tends to effect the closing of all of the switches. When the motor circuit is completed, a heavy rush of current traverses a circuit comprising line conductor 65, armature 67, resistors 68 and 70 coils 62, which are connected in series and arranged alternately in the circuit, to the line conductor 66. All of the switch members are accordingly retained in their open 75 positions.

When the current traversing the armature circuit falls to a predetermined value, the force tending to close switch member 56 is greater than that exerted by the corresponding series coil 62, and the switch closes to 80 shunt the corresponding resistor 68. This shunt circuit includes, also, a portion of the coil 62 for retaining the switch 57 in its open position. A second rush of current occurs 85 upon the closing of switch 56, and switch 57 is held in its open position until the current again falls to the predetermined value. In a similar manner, the switches 58 and 59 close in order to shunt the corresponding resistors 68 and thereby accelerate the motor 90 to its normal speed.

The arrangement shown in Figs. 6 and 7 is similar to that shown in Fig. 4 in that a single actuating coil is employed for effecting the closing of several switches in 95 sequence. Separate series coils are provided for the several switch members for controlling the closing of the switches in accordance with the value of the current traversing the circuit controlled by the switches. A 100 switch of the character just described constitutes a neat and compact device which occupies comparatively small space and may be manufactured more easily and with 105 greater economy than a corresponding number of separate switches for accomplishing the same results.

It will be noted that systems arranged in accordance with those illustrated in Figs. 4, 5 and 6 operate automatically to effect the acceleration of electric motors either of the alternating-current or direct-current type. A 110 substantially constant force is available, at all times, during the acceleration of the motor to effect the closing of each switch. 115 The force opposing that of the closing coil is variable and the switch is closed practically instantly upon the decrease of the opposing force below a predetermined value. This predetermined value may be varied by 120 adjusting the core members. This arrangement insures that the switches operate promptly in accordance with the value of the current in the motor circuit. When a single series coil is employed, the actuating 125 force, which is variable, may fall below that required to overcome the inertia of the movable parts before the switch is closed.

Switches constructed in accordance with my invention are particularly adapted for 130

use in connection with hoists that operate at high speeds, gearless traction elevators or mine hoists embodying spur gear mechanism. In the above and similar machines, it frequently occurs that the loads operate the motors as generators. In such case, the current traversing the motor circuit decreases so rapidly that series lockout switches could not operate during the brief interval in 10 which the armature current was of sufficient value to effect their closing. By employing actuating coils that are energized independently of the current traversing the motor circuit, the closing of the switches is insured 15 regardless of whether the motor operates as a motor or as a generator.

By employing a spring which permits movement of the armature member controlled by the shunt coil relatively to the 20 switch member to which it is operatively connected, the force for closing the switch is a maximum at the beginning of the closing movement. Since the armature member assumes its operative position upon the 25 closing of the circuit of the shunt coil, the spring is placed under maximum stress and its force is available when the opposing force falls below the predetermined value.

In a switch of the usual construction, the 30 closing force is at a minimum value at the beginning of the movement because of the relatively large air gap between the core member and the armature member of the electromagnet. The closing force increases 35 rapidly as the air gap is decreased, and a considerable shock occurs upon the engagement of the switch members.

I claim as my invention:

1. In an electromagnetically operable 40 switch, the combination with a base, a switch member pivotally mounted thereon, a pair of armature members movable relatively to each other and to said switch member and pivoted upon the pivot of said switch member, and means for operatively connecting all of said members, of electromagnetic means tending to actuate said armature members for moving said switch member in opposite directions.

50 2. In an electromagnetically operable switch, the combination with a movable switch member, of means tending to actuate said member in opposite directions, said means comprising an actuating coil and a 55 retaining coil having a normal number of turns and an abnormal number of turns the latter of which are adapted to be rendered ineffective under predetermined conditions.

3. In an electromagnetically operable 60 switch, the combination with a movable switch member, of means tending to actuate said member in opposite directions, said means comprising an actuating coil and a retaining coil having an intermediate con-

nection for rendering a portion of said coil 65 ineffective under predetermined conditions.

4. In an electromagnetically operable switch, the combination with a movable switch member, of means tending to actuate said member in opposite directions, said means comprising an actuating coil and a retaining coil having a normal number of turns and an abnormal number of turns for preventing the operation of said switch under normal operating conditions, said abnormal number of turns being adapted to be shunted under predetermined conditions.

5. The combination with a plurality of movable switch members and a single means for exerting a substantially constant force 80 for effecting the operation of said switch members in one direction, of separate means for opposing the operation of the respective switches, and means for varying the force of each of said separate means.

6. The combination with a plurality of movable switch members and a single shunt coil for tending to effect the operation of all of said members, of a separate series coil for retaining each of said members in one 90 position.

7. The combination with a plurality of movable switch members and a single shunt coil for tending to effect the operation of all of said members, of a series coil for retaining each of said members in one position, each of said series coils except that of the first switch to close having a number of turns in excess of those required during normal operation of the switch and that are 100 controlled by the preceding switch to operate.

8. The combination with a plurality of movable switch members and a single shunt coil for tending to effect the operation of 105 all of said members, of a series coil for retaining each of said members in one position, and means comprising a portion of certain of said series coils for insuring the operation of said switch members in a pre- 110 determined order.

9. The combination with a base and a stationary contact member and a pivoted contact member supported thereby, of a pair of armatures pivotally mounted upon the 115 pivot of said pivoted contact member, a spring tending to maintain said armatures separated, a spring tending to maintain one of said armatures and said pivoted contact member separated, a shunt coil for actuating said other armature to cause the engagement of said contact members, and a series coil for actuating said one armature to prevent said engagement.

10. An electromagnetic switch comprising 125 an energizing winding and a magnetic structure therefor, a pivoted switch arm normally in open position and held in closed

position by a force set up by said winding acting on one side of the pivot, a holding-out winding acting on the same side of the pivot to hold the switch arm in open position, and a member moved by the energizing winding to set up a force which becomes effective to move the switch member in a closing direction when the current in the holding-out winding drops to a predetermined value.

11. An electromagnetic switch comprising an energizing winding and a magnetic structure therefor, a pivoted switch arm normally in open position and held in closed position by a force set up by said winding

acting on one side of the pivot, a holding-out winding acting on the same side of the pivot to hold the switch arm in open position, and a member moved by the magnetic force of said energizing winding acting on the other side of the pivot to set up a constant force which becomes effective to move the switch member in a closing direction when the current in the holding-out winding drops to a predetermined value. 20

25 In testimony whereof I have hereunto subscribed my name this 15th day of Dec. 1916.

BENJAMIN McINNERNEY.
